UNITED STATES PATENT OFFICE.

MAURICE GROSS AND FRANCIS P. FREBAULT, OF JACKSONVILLE, OHIO.

PACKAGE-TIE.

Patent No. 906,413.

Specification of Letters Patent.

Patented Dec. 8, 1908.

No. 906,413.

Application filed March 18, 1908. Serial No. 421,877.

To all whom it may concern:

Be it known that we, MAURICE GROSS and FRANCIS P. FREBAULT, citizens of the United States, residing at Jacksonville, in the county 5 of Athens and State of Ohio, have invented new and useful Improvements in Package-Ties, of which the following is a specification.

This invention relates to a bundle or package tie of that type consisting of a fastener 10 attached to one end of a cord or other flexible element and so designed that the other or free end of the cord can be securely fastened without tying a knot therein and without requiring the cord to be cut when it 15 is desired to open the bundle.

The invention has for one of its objects to improve and simplify the construction of devices of this character so as to be comparatively simple and inexpensive to manufacture, readily manipulated, and especially designed for tying bundles of letters or other mail matter and the like.

Another object of the invention is to provide a package tie having a metal piece attached to one end of the cord, the said piece being designed to permit the cord to be fastened both lengthwise and crosswise of the bundle, or only crosswise, as occasion may require.

With these objects in view and others, as will appear as the description proceeds, the invention comprises the various novel features of construction and arrangement of parts which will be more fully described 35 hereinafter and set forth with particularity in the claims appended hereto.

In the accompanying drawing, which illustrates certain embodiments of the invention, Figure 1 is a plan view of a bundle of letters 40 or the like showing the improved tie applied thereto. Figs. 2 and 3 are sections of the metal piece on lines 2--2 and 3--3, respectively. Fig. 4 is a plan view of a bundle showing a modified form of tie. Fig. 5 is a 45 sectional view on line 5--5, Fig. 4.

Similar reference characters are employed to designate corresponding parts throughout the several views.

Referring to the drawing, and more particularly to Fig. 1, 1 designates a cord or other flexible element which has one end tied into a knot to form a stop to prevent the cord from becoming detached from the metal piece or body 2 of the device, the said piece

having a depression 3 for accommodating the 55 knot, and the said depression has an aperture 4 through which the cord passes. The body 2 is provided with parallel fingers 5 that are spaced apart to form recesses 6 into which the cord can be engaged, the extremities of the fingers being alternately bent in opposite directions so as to permit of the free insertion of the cord in the recesses 6. The corner of the plate of the body 2 diametrically opposite from the knot-receiving depression 3 is bent upwardly to form a lug 7 that has an aperture 8 through which the cord 1 passes directly from the aperture 4. The body piece is provided with a slot 9 extending inwardly from the edge opposite from 70 that having the fingers 5 and inclined downwardly, and the bottom edge of the body is formed with a V-shaped notch 10 which terminates adjacent the inner end of the slot 9 so as to receive the free end of the cord. 75

The tie 2 shown in Fig. 1 is designed more especially for fastening the cord that passes only one way around the bundle. The tie is applied to the bundle at the top thereof and the cord passed around the bundle immediately from the lug 7 and the free end of the cord is engaged in the slots 6, thence continued across the tie and over the extremity of the cord between the apertures 4 and 8, and the free end is then engaged in the slot 9 85 and finally in the notch 10. To release the tie, it is merely necessary to take hold of the free end thereof and disengage it from the notch 10 and then from the recesses 9 and 6 respectively. The body 2 has an aperture 11 90 whereby the tie can be hung up on a nail or peg when not in use.

The tie shown in Fig. 4 is so designed as to permit the cord to be tied around the bundle both lengthwise and crosswise thereof or in 95 one direction around the same. The tie is substantially similar to that shown in Fig. 1, except that it is provided with a hook 12 preferably stamped out therefrom at a point adjacent the inner end of the topmost finger 5 and is provided with an aperture 13 adjacent the knot-receiving depression 2 and one of the fingers 5 is wider than the others and has an opening 14 whereby the tie can be hung up on a nail when not in use. The cord 1 is secured to the tie by the knotted end being retained in the depression 2 and the cord is threaded through the opening 13 directly

from the opening of the said depression. In applying the device to a package, the cord is passed around the package in one direction and engaged under the hook 12 and then 5 passed around the package in a plane at right angles to the first wind of the cord and the free end of the cord is secured to the tie in the same manner described in connection with Fig. 1. In case the bundle is too large 10 for permitting the cord to be wound longitudinally and transversely around the package, the cord is unthreaded from the opening 13 and threaded through the opening 8 in the lug 7 so that the tie can be used in the manner 15 described in relation to Fig. 1.

From the foregoing description, taken in connection with the accompanying drawing, the advantages of the construction and of the method of operation will be readily apparent 20 to those skilled in the art to which the invention appertains, and while we have described the principle of operation of the invention, together with the device which we now consider to be the best embodiment 25 thereof, we desire to have it understood that the device shown is merely illustrative, and that such changes may be made when desired as are within the scope of the claims.

Having thus described the invention, what we claim is:—

1. A package tie comprising a body piece having a knot-receiving depression, a plurality of cord-engaging fingers, a lug extending outwardly from the plane of the body piece and provided with an aperture for receiving the cord, and a finger provided with a notch for receiving the extremity of the cord. 30

2. A package tie comprising a metal plate having a cord-receiving aperture and a depression at the aperture for receiving a knot in the cord, spaced fingers projecting from one edge of the plate, an apertured lug at one corner of the plate, a notched finger on the plate and cooperating with one edge thereof to 40 form a cord-receiving recess, and a hook rising from the plate adjacent the first-mentioned fingers. 45

In testimony whereof we affix our signatures in presence of two witnesses.

MAURICE GROSS.
FRANCIS P. FREBAULT.
